UNITED STATES PATENT OFFICE.

BERNARD H. JANSEN, OF CLEVELAND, OHIO.

DESIGN FOR A FAUCET-HANDLE.

No. 39,269.

Specification for Design.

Patented April 21, 1908.

Application filed February 14, 1908. Serial No. 415,965. Term of patent 7 years.

To all whom it may concern:

Be it known that I, BERNARD H. JANSEN, a citizen of the United States, residing at Cleveland, in the county of Cuyahoga and State of Ohio, have invented a new original Design of a Faucet-Handle, reference being had to the accompanying drawings, forming part thereof.

In the accompanying drawings Figure 1 is

a plan view of the design, and Fig. 2 is a side elevation thereof.

What I claim is:

The ornamental design of a faucet handle as shown.

BERNARD H. JANSEN.
